UNITED STATES PATENT OFFICE.

IVAN N. ELY, OF MINNEAPOLIS, MINNESOTA.

AUTOMOBILE HEATER.

Application filed March 2, 1925, Serial No. 12,788. Renewed October 22, 1926.

My invention relates to automobile heaters of the manifold type in which the manifold and heater are cast integral.

My invention has as its object to provide 5 a heater especially adapted to deliver a current of warm air immediately after the starting of the engine to which it is attached.

More particularly, it is my object to provide a heater in which the ordinary manifold is provided with an air tube extending 10 through it from one end wall to the other and positioned to receive directly the exhaust gases from the engine, and to be entirely surrounded by such exhaust gases.

15 A further object is to provide means for conducting the air current to the aforesaid air tube, and conducting it from said tube to the interior of the automobile, said means also serving to provide an auxiliary air passage 20 on the exterior of the manifold in order to increase the capacity of the heater.

25 A further object is to provide a heater which is cast entirely in one integral casting, and is at the same time of simple, durable and inexpensive construction.

With these and other objects in view, my invention consists in the construction, arrangement and combination of the various parts of my device, whereby the objects contemplated are attained, as hereinafter more 30 fully set forth, pointed out in my claim, and illustrated in the accompanying drawings, in which:

Fig. 1 is an elevation of an engine to 35 which my heater is attached, a portion of the floor boards of the automobile being shown in section.

Fig. 2 is a vertical transverse section 40 through the heater, taken on the line 2-2 of Fig. 3.

Fig. 3 is a vertical longitudinal sectional view through the heater, taken on the line 3-3 of Fig. 2.

Fig. 4 is a plan view of the heater, partly 45 in section, taken on the line 4-4 of Fig. 3.

Fig. 5 is a side elevation of the heater.

I have used the reference character 10 to indicate generally an engine of a common 50 type of automobile, which has the intake manifold, 11, and the exhaust pipe, 12. The dash of the automobile is indicated at 13, and the foot boards at 14. The ordinary exhaust manifold comprises a longitudinal tube member, 15, having the four elbows, 16, which serve to connect the manifold with the exhaust ports of the engine. The rear

end of the manifold tube, 15, is bent rearwardly and downward as at 16^a, and threaded at 17 to receive the packing nut, 18, connecting the manifold with the exhaust 60 pipe, 12.

In order to remedy the objections of the heaters now in use, the integral heater cast in one piece with the manifold has been provided, which has the advantage of serving to 65 heat the air on all sides instead of on one. That is, the heat from the manifold is conducted almost instantly by conduction throughout the metal walls of the air duct, and the current of air is thus surrounded on 70 all sides by heated metal walls and absorbs more heat in passing.

Another objection which may be had against the heater which attaches around the old manifold is that the currents of air 75 tend to absorb disagreeable odors from the surface of the manifold and engine block, caused by accumulations of oily material thereon. The integral construction does away with these objections. 80

My invention is aimed, primarily, to improving the integral type heater by employing an air tube which is situated within the manifold itself and exposed directly to the exhaust gases on all sides thereof. There 85 are certain problems in construction of a manifold embodying such a heating tube which my invention solves.

The size which may be given to the inner heating tube is limited since it is desirable 90 to maintain the general proportions of the manifold about the same, and at the same time not obstruct the flow of the gases on the interior thereof.

I have used the reference character, 19, 95 to indicate the inner air tube, which is of seamless steel tubing, having its ends cast into the end walls, 20 and 21, of the manifold.

In casting the manifold the sand core used 100 to form the hollow interior thereof is baked around the steel tube, 19. The ends of the tube, 19, are allowed to project beyond the core approximately the thickness of the walls, 20 and 21, so that when the manifold 105 is cast around the core, the tube will become united integrally with the manifold casting. Upon removal of the sand of the core, the interior of the manifold will have the construction shown in Fig. 3. 110

The manifold is enlarged somewhat in width to preserve practically the same

cross-sectional area between its walls and the tube, 19, as formerly was had in the old type manifold.

In order to provide sufficient circulation 5 of air, the auxiliary air duct, 22, is formed on the outer side of the manifold. The air duct, 22, follows the general contour of the tubular portion, 15, of the manifold, but does not cover the elbows, 16. This is illustrated in Fig. 5.

The current of air passing through the inner air tube, 19, will, especially during the first fifteen minutes or so of the running 15 of the engine, deliver a much hotter current of air than the outer air duct, 22, and as a result it is desirable that the air from the air duct, 22, be mixed thoroughly with the heated air from the tube, 19, before it is discharged into the interior of the car. The 20 air duct, 22, is therefore continued around the rear end wall, 20, of the manifold, as at 23, and thence continued along the plane of the manifold proper, as at 24.

The portion, 24, which may be called the 25 neck of the heater, is aligned with the tube, 19, as illustrated in Fig. 4, and the air current from the duct, 22, will thus first strike the air current from the tube, 19, in a transverse direction so as to tend to break up 30 the current from the tube, 19, and will then tend to completely envelop what remains thereof so as to most completely mix therewith.

A simple butterfly valve, 25, may be provided 35 in the discharge end of the neck, 24, to regulate the flow of air therefrom. At the forward end of the manifold the air duct, 22, is spread around the end of the manifold to form a somewhat ball-shaped 40 receiving cup, 26, to receive the current of air from the fan of the car.

It will now be seen that the tube, 19, will receive the direct heat from the exhaust 45 when the engine is started and will almost immediately commence to discharge a warm stream of air into the neck, 24. Sufficient heat will be given off thereby to warm the current of air passing through the duct, 22, so that the heater will not discharge a current 50 of cold air into the car when the car is started. After the engine has operated for some time the manifold will become heated

to a high degree of temperature, and the walls of the duct, 22, will become heated in the same way by conduction. The current 55 of air passing therethrough will therefore be considerably hotter than that produced in the ordinary attachable type heater.

The neck, 24, is inclined upwardly somewhat in order that it may extend through 60 the floor boards, 14, of the car at the highest point thereof, and also in order that it may not interfere with the exhaust pipe nut, 18.

Some changes may be made in the construction and arrangement of the parts of 65 my invention without departing from the real spirit and purpose of my invention, and it is my intention to cover by my claim any modified forms of structure or use of 70 mechanical equivalents which may be reasonably included within its scope.

I claim as my invention:

In a combined exhaust manifold and vehicle heater, a manifold proper in the form of an elongated tube having a rear downwardly bent exhaust pipe and a rear wall forming part thereof, and having a front wall; a longitudinal air duct formed on the side of the manifold and integral therewith, said air duct extending around the 75 rear wall of the manifold and having a discharge neck extending rearwardly from the manifold and having its axis disposed substantially in the same vertical plane with the vertical axis of the manifold, said air 80 duct having an intake bell at its forward end extending substantially across the end of the manifold, and an interior air tube having its ends united with the forward and rear walls of the manifold, spaced from the 85 sides of the manifold and extending longitudinally thereof, said tube communicating at its ends with the bell and the discharge neck, respectively, of the air duct, being positioned to receive directly against the 90 outer surface the exhaust gases passing through the manifold, and the discharge mouth of said air tube being positioned centrally of said discharge neck.

Signed at Remsen, in the county of Plymouth and State of Iowa, this 3rd day of February, 1925.

IVAN N. ELY.
